GARMENT HANGER

John T. Lancaster, Harper Woods, Mich.

Application July 12, 1954, Serial No. 442,679

16 Claims. (Cl. 223—92)

This invention relates to a garment hanger.

The garment hanger of the present invention is especially useful for carrying garments in an automobile; although it will be appreciated that the garment hanger is useful in many other situations. Garments supported from a hook in an automobile by the ordinary hanger are likely to become soiled or wrinkled especially where crowded conditions prevail. On the other hand when garments are packed in traveling bags they are invariably wrinkled as a result. The present invention is intended to overcome these difficulties.

One object of this invention is to provide a garment hanger which is particularly designed to support a frock or similar article of clothing without wrinkling.

Another object of the invention is to provide a garment hanger which conveniently supports an article of clothing in a relatively small package.

Still another object of the invention is to provide a garment hanger which is of simple construction, composed of a relatively few inexpensive parts, and yet extremely capable in the performance of its intended function.

Other objects of the invention will become apparent as the following description proceeds, especially when taken in connection with the accompanying drawings, wherein:

Figure 1 is an elevational view of a garment hanger constructed in accordance with the present invention;

Figure 2 is a sectional view taken along the line 2—2 on Figure 1;

Figure 3 is an elevational view of a modified form of garment hanger, also constructed in accordance with this invention, and showing the dotted outline of a frock supported thereby;

Figure 4 is an elevational view showing the garment hanger of Figure 3 in folded condition;

Figure 5 is an elevational view of another form of garment hanger likewise embodying the present invention;

Figure 6 shows a fragmentary detail of a portion of Figure 5;

Figure 7 is an elevational view of a further modification of garment hanger;

Figure 8 is an enlargement of a portion of Figure 7; and

Figure 9 is a sectional view taken along the line 9—9 on Figure 8.

Referring now more particularly to the drawing and especially to Figure 1, the garment hanger there illustrated comprises an upper frame 10, a lower frame 11, a garment hanger proper 12 at the top of the upper frame, and a return hanger 13 at the bottom of the lower frame.

The upper frame 10 is of one piece wire construction and comprises the laterally spaced side bars 14 and 15. The side bar 14 includes the upper and lower portions 16 and 17 integrally connected together by a laterally extending portion 18. The side bar 15 includes the upper

2

and lower portions 19 and 20 integrally connected together by a laterally extending portion 21. A transverse bar 22 extends between the lower ends of the side bars and loop portions 23 integrally connect opposite ends of the transverse bar with the lower ends of portions 17 and 20 of the side bars.

The garment hanger proper 12 comprises a resilient elongated bar 24 which has the opposite end portions return bent to provide garment supporting arms 25 and 26 which extend towards each other in crossing relation. A wire member 27 has a curved portion providing a hook 28 for suspending the garment hanger from a fixed support, and the wire member has a coiled portion 29 encircling and slidably receiving the arms 25 and 26 at the point of crossing thereof. The coiled portion 29 of wire member 27 terminates in an upturned hook receiving part 30 (Figure 2) for a purpose to be described hereinafter. The arms 25 and 26 terminate in loop portions 31, and the upper ends of portions 16 and 19 of the side bars also are formed to provide loop portions 32 respectively engaging with the loop portions 31 to provide a hinge connection.

The lower frame 11 is of one piece wire construction and includes side bars 33 and 34 having loop portions 35 at the upper ends respectively engaging with loop portions 23 to provide a hinge connection with the upper frame permitting the lower frame to be folded upon the upper frame. A transverse bar 36 has its opposite ends integrally connected to the lower ends of side bars 33 and 34 by loop portions 37.

The return hanger 13 comprises a transverse bar 38 extending across the lower end of frame 11 having its opposite ends formed to provide loop portions 39 respectively engaging with loop portions 37, and the intermediate portion of bar 38 is provided with an offset defining a hook 40 which is engageable with the hook receiving part 30 in the folded condition of the frames.

The manner in which a garment, such as a frock, is supported on the garment hanger thus described will be understood readily and upon reference to Figures 3 and 4 described below. The shoulder portions of the frock will be supported upon arms 25 and 26 of the hanger proper with the middle portion thereof to the rear of transverse bar 22 and the lower or skirt portion thereof in front of transverse bar 36 but to the rear of bar 38. The frock may then be folded to provide a compact package by merely raising the lower frame and folding the same over upon the upper frame, and engaging hook 40 over the hook receiving part 30 to releasably retain the hanger in its folded condition.

Referring now to Figures 3 and 4, a slightly different form of the invention is illustrated. The upper frame of the garment hanger illustrated in Figure 2 comprises the upwardly inclined side bars 41 and the lower transverse bar 42 integrally connected to the lower ends of side bars 41 by loop portions 43. The lower frame consists of the side bars 44 and 45 having loop portions 46 at their upper ends respectively engaging with the loop portions 43 of the upper frame.

A return hanger is provided at the bottom of the lower frame and consists of a transverse bar 47 having the arms 48 and 49 integrally connected to opposite ends thereof by loop portions 50, the latter engaging with loop portions 51 at the lower ends of bars 44 and 45. The inner ends of arms 48 and 49 are wound around each other to provide a fixed connection and the arm 48 terminates in a hook 52.

The garment hanger proper is generally indicated at 52' and consists of the bar 53 and having the opposite ends return bent to provide garment supporting arms 54 and 55 which extend towards each other and intertwined at their inner ends to provide a fixed connection. The

arms 54 and 55 are formed to provide integral loop portions 56 respectively engaging with the loop portions 57 at the upper ends of side bars 41. A wire member 58 projects upwardly from the hanger proper having a curved hook portion 59 and a coiled portion 60 fixedly secured to the inner ends of arms 54 and 55. The coiled portion 60 terminates in a loop providing a hook receiving part 61 for receiving hook 52 in the folded condition of the hanger.

Figures 5 and 6 illustrate still another form of the invention. The upper frame of the garment hanger illustrated in Figures 5 and 6 is of one piece wire construction and includes side bars 62 and 63. Side bar 62 includes the laterally spaced portions 64 and 65 integrally connected by the laterally extending portion 66. Side bar 63 includes the laterally spaced portions 67 and 68 integrally connected by a laterally extending portion 69. A transverse portion 70 integrally connects the upper ends of portions 64 and 67 and is formed with an intermediate loop 71 and a terminal downwardly extending loop 72 which defines a hook receiving part. The lower ends of portions 65 and 68 of the side bars are shaped to provide the loop portions 73 having a terminal portions 74 and 75 extending towards each other and interlaced at their inner ends. A transverse bar 76 has loop portions 77 at the opposite ends encircling the side bars 65 and 68 to maintain the latter in fixed spaced relation.

The hanger proper 78 is of the ordinary type having the lower transverse portion 78' and the return bent garment supporting arms 79 and 80 which extend inwardly and through the intermediate loop 71 of the upper frame and upward therefrom where they are interlaced together. One of the arms has an upwardly curved portion providing a hook 81 for supporting the hanger on a fixed mounting. The upper frame is supported upon the hanger proper by reason of the loop portion 71 resting upon the arms 79 and 81.

The lower frame includes the side bars 82 and 83. The upper ends of these side bars are formed with loop portions 84 respectively engaging with the loop portions 73 to provide a hinge connection permitting the lower frame to be folded upon the upper frame. The return hanger 85 is identical with the hanger 78 and the lower ends of bars 82 and 83 are provided with loop portions 86 through which the transverse bar of the return hanger 85 extends. A transverse bar 87 extends between the lower ends of side bars 82 and 83 having loop portions 88 at the opposite ends respectively encircling the side bars for maintaining the latter in fixed spaced relationship.

In the folded condition of the garment hanger illustrated in Figures 5 and 6, the hook 89 of the return hanger engages the hook receiving part 72 to maintain the folded relationship.

A still further form of the invention is illustrated in Figures 7-9. The hanger proper 90 is of exactly the same construction as the hanger proper 78 illustrated in Figure 5 with the exception that the inner ends of the arms 91 and 92 are provided with the laterally extending shoulders 93 and 94. A plate 95 is folded over the shoulders 93 and 94 having a central opening 95' for receiving the upwardly projecting inner ends of the arms 91 and 92 of the hanger proper and also to provide a hook receiving part. The opposite panels 96 and 97 of the plate are provided with registering openings 98 and 99 for respectively receiving the upper looped ends of side bars 100 and 101 of the upper frame. The upper frame is completed by the transverse bar 102 having loop portions 103 at the opposite ends respectively engaging loop portions 104 at the lower ends of the side bars.

The lower frame includes side bars 105 and 106 having loop portions 107 at the upper ends respectively engaging the loops 103 of the transverse bar, and the lower

looped ends 108 of side bars 105 and 106 are connected together by a transverse bar 109.

The return hanger consists of a transverse bar 110 having looped end portions 111 engaging the opposite looped ends of transverse bar 109, and an intermediate portion of transverse bar 110 is formed to provide a hook 112 for engaging the hook receiving part 95' in the folded condition of the hanger.

What I claim as my invention is:

1. A garment hanger comprising an upper frame and a lower frame, said upper frame comprising a pair of laterally spaced side bars, means at the top of said upper frame providing a hook for supporting said hanger and members projecting laterally outwardly from said hook for supporting a garment thereon, the lower frame comprising a pair of laterally spaced side bars having their upper ends respectively hingedly connected to the lower ends of the first-mentioned side bars permitting said lower frame to be folded upon said upper frame, a transverse bar connecting the lower ends of the second-mentioned side bars, means on said upper frame providing a first part, and means on said lower frame providing a second part releasably engageable with said first part in the folded condition of said frames to retain said frames in folded condition.

2. A garment hanger as defined in claim 1 having a second transverse bar connecting the lower ends of the first-mentioned side bars.

3. A garment hanger as defined in claim 2 in which said last-named means comprises a third transverse bar having its opposite ends connected to the lower ends of the second-mentioned side bars and having an intermediate portion shaped to provide the second part, and in which one of said parts is in the form of a hook and the other is in the form of a hook-receiving part adapted to receive said hook.

4. A garment hanger comprising an upper frame and a lower frame, said upper frame comprising a pair of laterally spaced side bars, garment supporting means at the top of said upper frame comprising a resilient elongated bar member having the opposite end portions return bent and extending toward each other in crossing relation, a hook for supporting said hanger having a portion encircling and slidably supporting said return bent portions at the point of crossing and having a first part, the upper ends of said side bars being respectively connected to the free ends of said return bent end portions, a transverse bar connecting the lower ends of said side bars, said lower frame comprising a pair of laterally spaced side bars having their upper ends respectively hingedly connected to the lower ends of the first-mentioned side bars permitting said lower frame to be folded upon said upper frame, a transverse bar connecting the lower ends of the second-mentioned side bars, and means at the lower end of said lower frame providing a second part releasably engageable with said first part in the folded condition of said frames to retain said frames in folded condition, one of said parts being in the form of a hook and the other being in the form of a hook-receiving part adapted to receive said hook.

5. A garment hanger comprising an upper frame and a lower frame, said upper frame being of one-piece wire construction and having a pair of laterally spaced side bars, a transverse bar extending between the lower ends of said side bars and loop portions integrally connecting the said lower ends to the ends of said transverse bar, garment supporting means at the top of said upper frame comprising a resilient elongated bar member having the opposite end portions return bent and extending toward each other in crossing relation, a wire member having a hook portion for supporting the hanger and having a portion encircling and slidably supporting said return bent end portions at the point of crossing and terminating in a first part, the upper ends of said side bars being connected to the ends of said return bent end portions, said

lower frame being of one-piece wire construction and having a pair of laterally spaced side bars having loop portions at their upper ends respectively interengaging the loop portions of the first-mentioned bars to provide hinge connections permitting the lower frame to be folded upon the upper frame, a second transverse bar integrally connected to the lower ends of the second-mentioned side bars, and means at the lower end of said lower frame providing a second part releasably engageable with said first part in the folded condition of said frames to retain said frames in folded condition, one of said parts being in the form of a hook and the other being in the form of a hook-receiving part adapted to receive said hook.

6. A garment hanger as defined in claim 5, in which said second transverse bar is integrally connected to the lower ends of said second-mentioned side bars by loop portions, and in which the last-named means comprises a third transverse bar having loop portions at the opposite ends respectively engaging the second-mentioned loop portions and having an intermediate portion shaped to provide the second part.

7. A garment hanger comprising an upper frame and a lower frame, said upper frame comprising a pair of laterally spaced side bars, garment supporting means at the top of said upper frame comprising a pair of wire members having their inner ends fixedly connected together and extending outwardly from the fixed connection, said members each being formed to provide an intermediate integral loop, the upper ends of said side bars having loop portions respectively inter-engaging with said loops, a hook for supporting said hanger secured to said members at the point of connection thereof and having a first part, a transverse bar connecting the lower ends of said side bars, the lower frame comprising a pair of laterally spaced side bars having the upper ends respectively hingedly connected to the lower ends of the first mentioned side bars permitting said lower frame to be folded upon said upper frame, a transverse bar connecting the lower ends of the second-mentioned side bars, and means at the lower extremity of said lower frame providing a second part releasably engageable with said first part in the folded condition of said frames to retain said frames in folded condition, one of said parts being in the form of a hook and the other being in the form of a hook-receiving part adapted to receive said hook.

8. A garment hanger comprising an upper frame and a lower frame, said upper frame comprising a pair of laterally spaced side bars, garment supporting means at the top of said upper frame comprising a pair of wire members having their inner ends fixedly connected together and extending laterally outwardly from the fixed connection, a wire hook projecting upwardly from the inner ends of said members for supporting the hanger, the upper ends of said side bars being connected by a cross bar having a first intermediate loop portion encircling said hook and supported on the inner ends of said members to suspend said upper frame from said garment supporting means and having a second intermediate loop portion providing a first part, a transverse bar connecting the lower ends of said side bars, the lower frame comprising a pair of laterally spaced side bars having the upper ends respectively hingedly connected to the lower ends of the first-mentioned side bars permitting said lower frame to be folded upon said upper frame, a transverse bar connecting the lower ends of the second-mentioned side bars, and means at the lower extremity of said lower frame providing a second part releasably engageable with said first part in the folded condition of said frames to retain said frames in folded condition, one of said parts being in the form of a hook and the other being in the form of a hook-receiving part adapted to receive said hook.

9. A garment hanger comprising an upper frame and a lower frame, said upper frame comprising a pair of laterally spaced side bars, garment supporting means at

the top of said upper frame comprising a pair of members having their inner ends fixedly connected together and extending laterally outwardly from the fixed connection, a hook projecting upwardly from the inner ends of said members for supporting the hanger, a plate carried by said members adjacent the inner ends thereof, the upper ends of said side bars being connected to said plate, said plate having an opening providing a hook-receiving part, a transverse bar connecting the lower ends of said side bars, the lower frame comprising a pair of laterally spaced side bars having the upper ends respectively hingedly connected to the lower ends of the first-mentioned side bars permitting said lower frame to be folded upon said upper frame, a transverse bar connecting the lower ends of the second-mentioned side bars, and means at the lower extremity of said lower frame providing a second hook releasably engageable with said hook receiving part in the folded condition of said frames to retain said frames in folded condition.

10. A garment hanger as defined in claim 9 in which the last-named means comprises a transverse bar having its opposite ends connected to the lower ends of the second-mentioned side bars and having an intermediate portion shaped to provide the second hook.

11. A garment hanger as defined in claim 10, in which said plate is folded over the inner ends of said members, and in which the opening therein providing said hook-receiving part also receives the upwardly projecting hook.

12. A garment hanger comprising an upper frame and a lower frame, said upper frame comprising a pair of laterally spaced wire side bars, garment supporting means at the top of said upper frame comprising a one-piece wire hanger member having an elongated bar member, the opposite end portions of said bar member being return bent and extending toward each other with the free ends of said return bent portions connected together, said hanger member including a hook portion for supporting the same extending upwardly from and in continuation of said free ends, a plate of inverted U-shape

13. A garment hanger comprising an upper frame having at the upper extremity a centrally disposed hook for supporting said hanger and portions extending laterally outwardly from said hook for supporting a garment, a lower frame having the upper extremity thereof hingedly connected to the lower extremity of said upper frame permitting said lower frame to be folded upon said upper frame, and releasable means on said frames cooperable to hold the latter in folded condition, said frames being formed of relatively rigid members to support a garment and protect it against wrinkling both in the folded and unfolded condition of said frames.

14. A garment hanger as defined in claim 13, said releasable means comprising a first part on said upper frame and a second part on said lower frame releasably engageable with said first part in the folded condition of said frames to retain said frames in folded condition.

15. A garment hanger as defined in claim 14, said

lower frame having a transverse part adjacent to the lower extremity thereof over which a portion of a garment may be suspended in the folded condition of said frames.

16. A garment hanger as defined in claim 15, including a transverse part extending substantially along the hinge axis over which a garment is folded in the folded condition of said frames. 5
